(57) **CLAIM**

We claim, the ornamental design for a computer signal cable socket, as shown and described.

DESCRIPTION

FIG. 1 is a top and front perspective view of a computer signal cable socket, showing our new design;

FIG. 2 is a front elevational view thereof;

FIG. 3 is a rear elevational view thereof;

FIG. 4 is a left side elevation view thereof, the right side elevation view is a mirror image thereto;

FIG. 5 is a top plan view thereof; and,

FIG. 6 is a bottom plan view thereof.
